UNITED STATES PATENT OFFICE.

THOMAS HALL, OF LYNDHURST, NEW JERSEY, ASSIGNOR TO THE THOMAS HALL COMPANY OF NEW JERSEY.

TYPE-WRITING MACHINE.

SPECIFICATION forming part of Letters Patent No. 453,593, dated June 2, 1891.

Application filed November 13, 1886. Serial No. 218,813. (No model.) Patented in England November 12, 1886, No. 14,675.

To all whom it may concern:

Be it known that I, THOMAS HALL, a citizen of the United States, residing at Lyndhurst, in the county of Bergen and State of New Jersey, have invented certain new and useful Improvements in Type-Writing Machines, (for which I obtained Letters Patent in Great Britain, No. 14,675, bearing date November 12, 1886;) and I do hereby declare that the following is a full, clear, and exact description of the invention, which will enable others skilled in the art to which it appertains to make and use the same.

My invention is designed to make an instrument of but few parts capable of printing a large number of characters.

The accompanying drawings show the detail of the mechanism, Figure 1 being a plan with part of index-plate removed. Fig. 2 shows a sectional elevation from left-hand end. Fig. 3 is a sectional plan showing paper-holding device and lower part of carriage. Fig. 4 is a sectional elevation showing method of operating type-cylinder. Fig. 5 is a sectional plan of the same. Fig. 6 shows the device for moving paper-rolls. Fig. 7 is a section of sheet under type-cylinder. Fig. 8 is edge view of the same. Fig. 9 represents a transverse section of the paper-roll and gears, showing the same in contact and in position for use; and Fig. 10 represents a similar view showing the rolls and gear separated and held apart for the insertion of the paper.

Like figures refer to like parts.

A represents the frame composed of rails A', ends A², and platen A³.

B represents carriage for carrying the printing mechanism.

B' is the lower part of carriage, to which B is hinged at B⁴, the whole moving on rails A', resting on wheels S, and guided by rollers or wheels S'.

B² are castings forming ends of carriage-frame.

B³ are bars forming sides of carriage-frame.

C represents the type-cylinder, formed of a thin shell of metal or rubber or both, and having the characters raised in certain localities on the surface.

C¹ is a cylinder on which C fits.

C' is a spur-gear turning on stud, which is fixed to sliding frame I, which drives cylinder C¹.

C² is a spur-gear which drives C'.

C³ is a spur-gear fixed at C², and which is made to revolve by rack D, which slides on part of sliding frame I.

E is a handle and pointer combined, which is hinged or fastened to rack D. It is made in two parts, one part passing between F and G, and provided with a conical point for entering the holes in F, the other part forming a handle, the point of which is over the conical point below, so that pointing to the letters printed on index G will bring the lower pointer into the proper hole to print from the corresponding character on cylinder.

F is a perforated plate with as many holes as there are characters on the cylinder C.

G is a plate placed above F, with printed characters representing the type on cylinder and so arranged that the characters on each correspond when used.

H is an ink-roller, of felt or other porous substance, turning in bearings in form 1, and in contact with the type on cylinder.

I is a frame made in such a way that it will carry printing-cylinder and ink-roller, and slide on the bars B³.

J is a sheet of metal or other material placed below the cylinder and hinged at same point as the carriage at B⁴.

J' is a portion of the sheet, which is made of thin flexible or elastic material, preferably india-rubber, and perforated so that one type can protrude.

K and K' are rollers, between which the papers to be printed is placed, the bearing of K being in frame A². The position of paper is shown in Fig. 2, Fig. 9 showing the paper-roll and gears in contact the same as they would be in use, the paper to be printed on between them and resting on platen A³, the gears being fixed on shafts of rollers K and K', as shown in Fig. 1 at K². Fig. 10 shows the rolls and gears separated and held apart by latch O' catching under rail A' for the insertion of the paper.

K^2 are spur-wheels gearing into each other, so that the rollers when in contact must turn together.

K^3 is a wheel on end of K , by which the rollers are turned.

K^4 is a plate swinging on shaft of roller K between K^3 and A^2 .

K^5 is a lever, the fulcrum of which is on a swinging plate K^4 and which drops by gravity and rests on a pin or stop on the side of the said plate K^4 . A point on the upper edge of the lever K^5 serves as a pawl to turn the wheel K^3 , catching into notches in the said plate when the said lever is lifted.

15 K^6 is a lever and pawl combined to act on K^3 , which drops to position shown in Fig. 6 when not in use.

L is a strip of metal forming a paper-holder and index for position of characters printed, 20 fixed to arms N on shaft O . The bearings of roller K' are in N .

O' is a lever on shaft O to separate the rollers.

P is a spring on B' , bearing up against middle B^3 to support cylinder away from the paper.

R is a pointer, fixed to B^2 , to indicate the place of the impression when printing.

To operate the machine, the paper is placed 30 over the platen A^3 and between the rollers by separating them and the paper-holder from the platen by pressing on lever O' . The printing mechanism, consisting of the cylinder in its frame and carriage, is placed at any 35 position on the rails desirable. The position of the printing-cylinder being indicated by pointer R , the handle E is moved to bring the index-point to the desired character on index G , thereby moving the cylinder up or down

40 lengthwise on bars B^3 and rotating it by the rack and gear D C^3 C^2 C' , the two movements combining to bring corresponding character on cylinder to the opening in sheet J , and a downward pressure presses the lower pointer

45 of handle into hole in F , thereby holding the cylinder firmly in place, and same pressure also carrying the whole frame downward, turning on hinge on carriage B^4 until the type protruding through J' touches the paper. Re-

moving the pressure, the spring P lifts the frame, and the same process can be repeated with any other characters, the process of writing causing the cylinder to move up by lines and rotate to position, and the rotation of the cylinder causes the ink-roller H , which is saturated with suitable ink, to continually reink the type. The carriage can be moved along on the rails A' in either direction by hand or by any of the methods now used for like purpose. The paper can be moved up or down 60 to any point by turning the wheel K^8 . To move the paper up by regular intervals, the lever K^5 is used, as shown here, one movement being one-sixth of a revolution of rollers.

Having described the construction and operation of this type-writer, what I claim as new in type-writing mechanism, and desire to secure by Letters Patent, is—

1. The combination, in a type-writer, of a type-cylinder sliding in the direction of its axis in a frame hinged at right angles to axis of cylinder, and the handle by which the cylinder and its frame are moved, and the cylinder rotated on its axis, and the pointer placed over and above the cylinder, and the index located between the pointer and the cylinder, substantially as shown and described.

2. In a type-writer, the sliding frame I , containing the type-cylinder C , with its toothed wheel, the axis of said cylinder being parallel to the line of movement of frame I , the rack D , engaging with the toothed wheel so as to rotate it, and the handle E , hinged to rack D at a right angle to the axis of the cylinder, 80 the whole combined and arranged to operate substantially as shown and described.

3. In a type-writer, the combination of the index-plate and the separate index above it, the double-pointed handle connected to the printing mechanism, the upper pointer pointing to the upper index and the lower pointer to locate itself on the index-plate, all arranged substantially as shown and described.

THOS. HALL.
